CLAUDE L. KEY, OF MILTON, OREGON, ASSIGNOR TO KEY WEEDER COMPANY, OF MILTON, OREGON, A CORPORATION OF OREGON

DUMPING MEANS FOR WEEDERS

Refiled for abandoned application Serial No. 172,315, filed March 3, 1927. This application filed September 25, 1929. Serial No. 395,163.

This application is filed in lieu of my abandoned application filed March 3, 1927, Serial No. 172,315.

This invention relates to dumping means for weeders and has as one of its objects to provide a dumping means adapted to operate by moving the weed cutting means in a vertical arc out of the ground and bringing it to a sudden stop to dislodge the cutweeds therefrom, and replacing the blade in the ground ready for operation.

Another object of the invention is to provide a dumping means for weeders having a toggle mechanism adapted to secure the cutting means in the operable position in the ground.

A further object of the invention is to provide a dumping means for weeders that is adaptable for tripping manually or by the aid of springs.

A further object of the invention is to provide a dumping means for weeders that will operate to automatically clean the blade and restore it to the operable position by means of a toggle mechanism and provide means to set said mechanism ready for action.

A further object of the invention is to provide a dumping means for weeders, a setting and a locking means, comprising a series of levers arranged for the purpose, and utilizing one of said levers to adjust the depth of operation of the blade in the ground.

A further object of the invention is to provide a dumping means for weeders, comprising a series of levers arranged for the purpose, and providing means to regulate the relative position of said levers to provide a locking arrangement that will lock the levers with varying degrees of security for manual or automatic release of the blade in case of contact with solid matter, as a stump or rock.

With these and other objects in view reference is now had to the accompanying drawings in which

Fig. 1 is a side elevation of one of the simplest forms of the device;

Fig. 2 is a similar view to Fig. 1 showing a remote setting means for the main actuating spring;

Fig. 3 shows a modified form of device with a remote blade regulating means;

Fig. 4 is a side elevation of a fourth modification of the device;

Fig. 5 is a side elevation of a fifth and preferred form of the device;

Fig. 6 is a plan view of a weeder showing the device installed;

Fig. 7 is a plan view of the tripping mechanism;

Fig. 8 is a side elevation thereof;

Fig. 9 is a partial sectional elevation of the tripping mechanism, taken on the line 14—14 of Fig. 8;

Fig. 10 shows a rear elevation of one form of latch;

Fig. 11 is a plan view of the crank assembly; and

Fig. 12 shows an enlarged fragment of the preferred form of device, showing its extreme movement by dotted lines.

Having reference to the drawings, like numerals refer to like parts throughout the several views, and the numeral 1 relates to weeders consisting of a frame 2 which may be of the usual construction, to which is attached a cutting blade 3, by means of goosenecks 4, the goosenecks being arranged to rock with said frame, as shown in Fig. 6, or to rock independent of said frame, as shown in Fig. 1, or otherwise.

The frame 2 is further provided with rearwardly extended members 5 supported at their rearward ends by castor wheels 6, or other means, and the whole suitably strengthened by diagonal members 7.

Mounted on the frame in a manner to be explained is a toggle operating mechanism 8 cooperating with a blade operating lever 9 that may be attached to the frame directly,

for direct operation of the blade, or through the medium of a rearwardly extending arm 10, to be extended by a link 11, to connect with the blade operating lever as shown in Figs. 1 and 2, and the toggle mechanism may be directly or indirectly attached thereto in the following described manner:

The toggle operating mechanism is arranged to utilize the maximum leverage of a toggle joint 12 at a time of greatest effort when the blade is being withdrawn or is entering the ground, this movement requiring the greatest power for successful operation.

To obtain this maximum power the toggle operating mechanism comprises a tripping arm 13 attached to the blade operating lever 9, this lever extending preferably upward for the purpose, and the tripping arm is adapted to form one arm of the toggle joint 12, and a locking and adjusting bar 14 is pivotally attached to the tripping arm, as at the pivotal point 15, and is extended for adjustable attachment preferably either to the blade operating lever or to the frame as by means of an upright 17 or to any point that will change the normal position of the blade with respect to the ground.

The adjustable feature of this bar consists of a series of holes contained therein whereby its effective length may be changed and thus advance or retract the blade operating lever thereby to regulate the depth of cut of said blade.

By referring to Fig. 5 it will be noted that the tripping arm 13, in this my preferred form, extends forward of the blade operating lever, to which it is pivotally attached, as at the pivotal point 18; that the locking and adjusting bar is pivotally attached to the tripping arm at the point 15 in advance of the pivotal point 18; and that this locking and adjusting bar extends rearward and is pivotally connected to the frame at the pivotal point 19, with the pivotal points normally being in line.

By this arrangement the toggle joint 12, formed by the tripping arm and the locking and adjusting bar, will assume the closed position when the blade is in the ground to operate with its maximum power as the blade enters or leaves the ground, the maximum power being obtained at the initial movement of the joint, which movement will disturb the alignment of the pivotal points.

From this it is obvious that by placing an adjusting screw 20 in the locking and adjusting bar, in a position cooperable with the tripping arm at its point 18 of pivotal connection with the blade operating lever that the position of the pivotal points of the toggle joint may be altered by its adjustment and permitted to pass over center and thus lock against any attempt at the release thereof, or by other adjustments of this screw it can be locked with a varying degree of se-

curity from that of a completely locked condition to that of a self releasing condition to be actuated on the blade contacting an unyielding object in the ground such as a rock or a stump.

Where the toggle joint is adjusted to the locked position a means to unlock said joint is necessary and is provided comprising a tripping post 21 which tripping post is preferably rigidly attached perpendicular to the outer end 22 of said tripping arm.

By this arrangement the upper end 23 of the tripping post 21 is extended out of line of the centers of said pivotal points so that a pull applied to the post, either locally or by a releasing rope 24, shown in Fig. 5, will pull from a point above the center of the pivotal points and thus unlock the operating mechanism.

In Fig. 1 the plain lever is shown as the tripping post and by advancing this lever it is obvious that the toggle joint will be tripped when the blade will be raised from the ground, either manually, or by a main spring 25 as shown. In my preferred form (Fig. 5) the main spring 25 is utilized to automatically advance this lever after tripping and has one of its ends 26 attached to a tension link 27 that in turn is pivotally attached to any convenient place on the tripping arm, thus to become adapted to yieldingly operate the mechanism to dump said blade by the normal movement of said tripping post.

By observing Fig. 12 it will be noted that a resetting spring 28 is provided attached to the forward end of the tripping arm and to the frame, wherewith to restore the toggle operating mechanism in the locked position.

This spring is of lesser strength than the main spring and is positioned in opposed relation thereto to enable the main spring, by its tension on the link 27 and as soon as unlocked, to open the toggle joint, the tripping arm pivoting on the pivotal point 15 of connection of the locking and adjusting bar therewith.

Now as the rear end of this bar is fixed with relation to the frame, the movement of the tripping arm will advance the blade operating lever and thus raise the blade out of the ground, with the maximum power obtaining as the blade leaves the ground, and the power diminishing as the tripping arm assumes the upright position, shown by the dotted lines in Fig. 12.

By again referring to Fig. 5 it will be further noted that the other end 29 of the main spring is attached to a movable tension arm 30 consisting primarily of a crank rotatably mounted in a suitable journal 31 secured to the member 5, and it will be further noted that in the locked position, as shown in Fig. 5, that a latch 32 is provided to secure the movable tension arm at a point away from said spring whereby the tension is main-

tained thereon, and further that a connecting rod 33 connects this latch operably with the blade operating lever.

Now by the advanced movement of the blade operating lever to nearly its maximum forward position this lever will exert a pull on the latch and move that member to release the movable tension arm, and as this arm moves forward the main spring will be released to loose its remaining tension, when the resetting spring will be free to pull the tripping arm back to the normal locked position.

As soon as the toggle joint has assumed this position the tension is restored in the main spring by the rotation of the tension arm which may obtain by a tension lever 34, as shown in Fig. 3, wherein it is indirectly connected to the shaft, or by means of a tension lever, as shown in Fig. 5, where a cable 35 extends from the lever to a sheave 36, the latter in turn being fixed to the shaft 37 of the tension arm whereby the tension arm may be rotated and the tension restored to the main spring for subsequent operation.

In Figs. 1, 2, 3, 4, 5, are shown the evolution of the device in the order named, Fig. 1 showing the blade attached to a separate beam, as before mentioned, and the blade connecting with the blade operating lever through the medium of the arm 10, link 11 and a crank 11^a, with the locking and adjusting bar 14 adjustably attached to the blade operating mechanism and extended rearwardly to form a toggle joint 12 with the tripping arm 13, that in turn is operated by the tripping post 21.

In Fig. 2 the same general principle prevails, with the main spring however being attached to the toggle pivot 15 and provided with a hook 39 that will engage a sheave 40 for securing in the manner represented by the dotted lines in this figure, engagement being obtained by the operation of the tension arm to the position shown dotted in this figure.

The device shown in Fig. 2 is placed under tension by advancing the tripping arm which sets the toggle joint in the locked position, this position being adjustable as before mentioned by the adjusting screw 20, which it is obvious is also applicable to that of Fig. 1. The hook 39 carries an extension member 41 that in turn is connected to the blade operating lever so that by the advance of the blade operating lever this lever will release the hook from the sheave and the tension of the main spring will be relieved until the blade is restored to its position in the ground, when the tension of the main spring will be restored in the manner explained.

In Fig. 3 the toggle operating mechanism is merely brought back on the frame and connected to the blade operating lever by means of a connecting link 42. In this device ad-

justment of the blade obtains through the hand lever 43 and quadrant 44.

The main spring in this case has the same tension restoring device and in addition there is equipped with a resetting spring that 70 operates to bring the toggle to the locked position, when the tension is released from the main spring in a manner identical with that described in Fig. 2.

In Fig. 4 the toggle joint is constructed of 75 two arms in a generally straight line with knees 46 attached to the arms to receive the adjusting screw 20 wherewith to adjust the sensitivity of the lock.

And in Fig. 5 the preferred form exhibits 80 the tension link 27 extending from the main spring, over and to a point on the tripping arm, the locking and adjusting bar extends rearward to the upright 17 on the journal 31 of the tension arm and is made adjustable 85 therewith by any suitable means whereby the blade operating lever may be advanced or retracted to adjust the depth of the blade in the ground.

With the arrangement shown in Fig. 5 and 90 from the above description, when the toggle joint is unlocked by pulling on the rope, the operating mechanism will assume the position shown by the dotted line in Fig. 12, and as soon as this condition prevails the latch 95 operates to release the tension arm. With the tension released from the main spring the resetting spring will restore the operating mechanism to the original normal position when by the movement of the hand lever 100 drawing the cable backward, rotating the sheave and with it the tension arm, the operating mechanism will be in a position ready for subsequent operation.

In use the adjusting screw is set to establish 105 the correct degree of security to the blade and the operation of weeding will be started.

Now should the blade strike a solid object, a sufficient movement of the blade operating lever will take place to trip the operating 110 mechanism.

Instantly upon tripping the mechanism, the main spring forces the blade against the frame, when at the same instant the tension on the main spring is released. The resetting 115 spring then restores the blade to the operative position in the ground, and locks for operation, when the tension may be restored in the main spring by the operator through the medium of the lever, and at his convenience.

Having thus described my invention, I 120 claim—

1. In a dumping means for weeders, a frame, a blade rockably attached to said frame, a toggle operating mechanism consisting of levers attached to said blade and arranged to exert their maximum power as the blade enters or leaves the ground, and further arranged to lock, and to secure the blade in the operable position in the ground,

means to vary the degree of security of the locking means, means to unlock said locking means, and means to yieldingly operate said levers to dump said blade.

5 2. In a dumping means for weeders, a frame, a blade rockably attached to said frame, a toggle operating mechanism comprising a tripping arm, adapted to form one arm of a toggle joint, and attached to said blade, and a locking and adjusting bar attached to the tripping arm to form the other arm of the toggle joint and attached to said frame, means to operate said toggle joint to apply its maximum power to the blade as
10 the blade enters or leaves the ground, means to lock said toggle joint to secure the blade in the operable position in the ground, means to vary the degree of security of the locking means from that of a completely locked condition to that of self releasing on the blade contacting an unyielding object in the ground, means to unlock said operating mechanism, and means to yieldingly operate the unlocked mechanism to dump said blade.

25 3. In dumping means for weeders, a frame, a blade rockably attached to said frame, a toggle operating mechanism comprising a tripping arm, adapted to form one arm of a toggle joint, and attached to said blade, and
30 a locking and adjusting bar attached to the tripping arm to form the other arm of the toggle joint and attached to said frame, means to operate said toggle joint to apply its maximum power to the blade as the blade
35 enters or leaves the ground, means to lock said toggle joint to secure the blade in the operable position in the ground, means to vary the degree of security of the locking means from that of a completely locked condition to that of self releasing on the blade contacting an unyielding object in the ground, means to unlock said operating mechanism, means to yieldingly operate the unlocked mechanism to dump said blade, and
40 45 means cooperating with the locking and adjusting bars to adjustably regulate the depth of cut of said blade.

4. In a dumping means for weeders, a frame, a blade rockably attached to said frame, a toggle operating mechanism attached to said weeder and comprising a tripping arm, adapted to form one arm of a toggle joint and attached to said blade, and a locking and adjusting bar attached to the tripping arm to form the other arm of the toggle joint and attached to said frame, means to operate said toggle joint to apply its maximum power to the blade as the blade enters or leaves the ground; means to lock said toggle joint to secure the blade in the operable position in the ground, means to vary the degree of security of the locking means from that of a completely locked condition to that of a self releasing condition as the blade contacts an unyielding object in

the ground, means to unlock said operating mechanism, means to yieldingly operate the unlocked joint to dump said blade, and means to restore the tension of the yielding means upon its operation being completed. 70

5. In a dumping means for weeders, a frame, a blade rockably attached to said frame, a toggle operating mechanism attached to said weeder and comprising a tripping arm, adapted to form one arm of a toggle joint and attached to said blade, and a locking and adjusting bar attached to the tripping arm to form the other arm of the toggle joint attached to said frame, means to operate said toggle joint to apply its maximum power to the blade as the blade enters or leaves the ground, means to lock said toggle joint to secure the blade in the operable position in the ground, means to vary the degree of security of the locking means from that of a completely locked condition, to that of a self releasing condition as the blade contacts an unyielding object in the ground, means to unlock said operating mechanism comprising a tripping post attached to said tripping arm and extended out of line of said toggle joint, means to yieldingly operate the unlocked joint to dump said blade, and means to restore the tension of the yielding means upon its operation being completed. 95

6. In a dumping means for weeders, a frame, a blade rockably attached to said frame, a toggle operating mechanism attached to said blade, said mechanism being arranged to apply its maximum power to the blade as the blade enters or leaves the ground, means to adjustably lock said mechanism to secure the blade in the operable position in the ground, means to unlock said operating mechanism comprising a tripping post attached thereto and extended out of line of said mechanism, a main spring adapted to yieldingly operate said mechanism to dump said blade, a resetting spring of lesser strength than said main spring and positioned in opposed relation thereto, attached to said mechanism, means to release the tension of the main spring immediately prior to its operation being completed, thereby permitting the resetting spring to relock said mechanism, and means to restore the tension of the main spring when said mechanism is relocked, for subsequent operation.

7. In a dumping means for weeders, a frame, a blade rockably attached to said frame, a blade operating lever attached to said blade, a toggle operating mechanism comprising a tripping arm attached to said blade operating lever and adapted to form one arm of a toggle joint, and a locking and adjusting bar attached to said frame and forming the other arm of said toggle joint, said toggle joint being adapted to apply its maximum power to the blade as the blade en- 30

- ters or leaves the ground, an adjusting screw incorporated in said toggle mechanism and adapted to permit the toggle joint to pass over center to lock and secure the blade in the ground with varying degrees of security, means to unlock said operating mechanism comprising a tripping post attached to said tripping arm and extended out of line of said toggle joint, a main spring attached to said 5 tripping arm and to said frame and adapted to yieldingly operate said toggle mechanism to dump said blade, a resetting spring of lesser strength than said main spring, attached to said tripping arm and to said frame, 10 and positioned in opposed relation to said main spring, means to release the tension of the main spring prior to its operation being completed, thereby permitting said resetting spring to relock said mechanism, and means 15 to restore the tension of the main spring for subsequent operation when said mechanism is relocked.
8. In a dumping means for weeders, a frame, a blade rockably attached to said frame, a blade operating lever attached to said blade, a toggle operating mechanism comprising a tripping arm attached to said blade operating lever and adapted to form one arm of a toggle joint, and a locking and 20 adjusting bar attached to said frame and forming the other arm of said toggle joint, said toggle joint being adapted to apply its maximum power to the blade as the blade enters or leaves the ground, means to advance 25 or retract said locking and adjusting bar to adjust the depth of cut of said blade, an adjusting screw incorporated in said locking and adjusting bar and cooperable with the tripping arm to form a lock to secure the blade in the ground with varying degrees of security, means to unlock said operating mechanism comprising a tripping post rigidly attached perpendicular to said tripping arm and extended out of line of said toggle 30 joint, a main spring attached to said tripping arm and to said frame and adapted to yieldingly operate said mechanism to dump said blade, a resetting spring of lesser strength than said main spring, attached to 35 said tripping arm and to said frame and adapted to release the tension of said main spring prior to its operation being completed, thereby permitting said resetting spring to automatically relock said mechanism, and means to restore the tension of the main spring for subsequent operation.
9. In a dumping means for weeders, a frame, a blade rockably attached to said frame, a blade operating lever attached to said blade, a toggle operating mechanism comprising a tripping arm attached to said blade operating lever and adapted to form one arm of a toggle joint, and a locking and 40 adjusting bar attached to said frame and forming the other arm of said toggle joint, said toggle joint being adapted to apply its maximum power to the blade as the blade enters or leaves the ground, means to advance 45 or retract said locking and adjusting bar to adjust the depth of cut of said blade, an adjusting screw incorporated in said locking and adjusting bar and cooperable with the tripping arm to form a lock to secure the blade in the ground with varying degrees of security, means to unlock said operating mechanism comprising a tripping post rigidly attached perpendicular to said tripping arm and extended out of line of said toggle joint, a main spring attached to said tripping arm and to said frame and adapted to yieldingly operate said mechanism to dump said blade, a resetting spring of lesser strength than said main spring, attached to 50 said tripping arm and to said frame and positioned in opposed relation to said main spring, means to release the tension of said main spring prior to its operation being completed, thereby permitting said resetting spring to automatically relock said mechanism, and means to restore the tension of the main spring for subsequent operation when said mechanism is relocked.
10. In a dumping means for weeders, a frame, a blade rockably attached to said frame, a blade operating lever attached to said blade, a toggle operating mechanism comprising a tripping arm attached to said blade operating lever and adapted to form one arm of a toggle joint, and a locking and 55 adjusting bar attached to said frame and forming the other arm of said toggle joint, said toggle joint being adapted to apply its maximum power to the blade as the blade enters or leaves the ground, means to advance or retract said locking and adjusting bar to adjust the depth of cut of said blade, an adjusting screw incorporated in said locking and adjusting bar and cooperable with the tripping arm to permit the toggle joint to pass over center and form a lock wherewith to secure the blade in the ground with varying degrees of security, means to unlock said operating mechanism comprising a tripping post rigidly attached perpendicular to said tripping arm and extended out of the line of the center of said toggle joint, a main spring attached at one end to said tripping arm and adapted to yieldingly operate said mechanism to dump said blade, a movable tension arm rotatably mounted on said frame and attached to the other end of said main spring, means to automatically trip said tension arm with a forward movement of said blade operating lever to release the tension of said spring, a resetting spring of lesser strength than said main spring attached to said tripping arm and to said frame and positioned in opposed relation to said main spring and adapted to restore the toggle mechanism automatically to the locked position upon release of the tension arm, and means to restore the tension to said main spring for subsequent operation.
11. In a dumping means for weeders, a frame, a blade rockably attached to said frame, a blade operating lever attached to said blade, a toggle operating mechanism comprising a tripping arm attached to said blade operating lever and adapted to form one arm of a toggle joint, and a locking and adjusting bar attached to said frame and forming the other arm of said toggle joint, said toggle joint being adapted to apply its maximum power to the blade as the blade enters or leaves the ground, means to advance or retract said locking and adjusting bar to adjust the depth of cut of said blade, an adjusting screw incorporated in said locking and adjusting bar and cooperable with the tripping arm to permit the toggle joint to pass over center and form a lock wherewith to secure the blade in the ground with varying degrees of security, means to unlock said operating mechanism comprising a tripping post rigidly attached perpendicular to said tripping arm and extended out of the line of the center of said toggle joint, a main spring attached at one end to said tripping arm and adapted to yieldingly operate said mechanism to dump said blade, a movable tension arm rotatably mounted on said frame and attached to the other end of said main spring, means to automatically trip said tension arm with a forward movement of said blade operating lever to release the tension of said spring, a resetting spring of lesser strength than said main spring attached to said tripping arm and to said frame and positioned in opposed relation to said main spring and adapted to restore the toggle mechanism automatically to the locked position upon release of the tension arm, and means to restore the tension to said main spring for subsequent operation.

forward movement of said blade operating lever to release the tension of said spring, a resetting spring of lesser strength than said main spring attached to said tripping arm and to said frame and positioned in opposed relation to said main spring and adapted to restore the toggle mechanism automatically to the locked position upon release of the tension arm, and means to rotate said tension arm to restore the tension of said main spring for subsequent operation.

In testimony whereof I affix my signature.
CLAUDE L. KEY.
